ABRADING TOOL

William E. Cowley and Wilfred M. McCord, Jr., Louisville, Ky., assignors to American Saw and Tool Company, Louisville, Ky., a corporation of Kentucky

Filed July 9, 1958, Ser. No. 51,716

Term of patent 14 years

(Cl. D37—1)

Figure 1 is a perspective view of an abrading tool showing our new design;

Figure 2 is a side elevational view thereof, both sides being of similar appearance;

Figure 3 is a top plan view thereof;

Figure 4 is an end view thereof taken from the right hand side of Figure 3;

Figure 5 is an end view of the abrading tool taken from the left hand side of Figure 3; and

Figure 6 is a fragmented sectional view taken along line 6—6 shown in Figure 2, showing on an enlarged scale the form of the corrugated surface on the front surface of the rear handle of the abrading tool.

The dominant features of the design reside in the portions shown in full line.

We claim:

The ornamental design for an abrading tool, substantially as shown and described.
